3,191,577 LIVESTOCK BARN

Paul H. McMurray, P.O. Box 126, Delphi, Ind.
Filed May 28, 1962, Ser. No. 198,030
6 Claims. (Cl. 119—16)

This invention relates to stock barns and more particularly to such a barn as is most suitable for raising pigs from the time they are born until they are marketable size.

The basic concept of the invention resides in the provision of a barn which will take care of all of the various requirements of hogs or pigs as the case may be from the time they are farrowed, through the period when they are being fattened for market and to the time of marketing, the barn itself being a small enough unit that a farmer of average means and having average facilities, can avail of a unit hereof or a series of such units in accordance with his ability to take care of the same and operate a stock raising operation along the lines suggested hereinafter.

Generally speaking, the basic concept of this invention is to provide what is essentially a circular enclosure within which the hogs may be penned in individual pens, providing for farrowing in such pens, thereafter changing the enclosure into a single pen and providing feeding and ventilating means as well as manure removal means to accommodate for all of the various phases of hog raising particularly.

Some of the basic problems in raising hogs, of course reside in the fact that a good many different diseases are periodically encountered in such operation, the necessity to have a substantial amount of help for feeding purposes, and an obvious advantage in fattening on a more rapid basis than has heretofore been contemplated, is within the clear contemplation hereof and provided by the facilities described herein.

Some of the fundamental features of the invention reside in the ability to supply feed on an automatic basis, maintain the stock in segregated areas where necessary, provide for the removal of manure as is necessary without manpower requirements of any substantial nature and further to provide ventilation and thus a suitable environment in which disease factors are reduced if not entirely eliminated.

With the foregoing in mind, it is a principal object of this invention to provide a stock barn of the class described, which is designed for erection in a unit of suitable size so that the same will provide for an economic number of hogs to be raised therein, satisfactorily feed the hogs after their birth and to the marketing period, at the same time reducing if not completely eliminating the manpower required for such operation.

A most desirable object of the invention resides in the fact that the unit as such can be duplicated without duplicating unnecessary facilities, all of the facilities provided being usable to the full extent for each individual group of hogs, and thus enabling the raising of any desired multiple of hogs within the capacity of each stock barn as herein described.

A further object of this invention is to provide means for feeding hogs which will greatly facilitate handling feed, by providing a central storage bin arranged in such a manner as to deliver feed to hogs which in turn are able to obtain the feed in the necessary quantities, whereby feed handling by manual means is reduced to a minimum if not entirely eliminated.

Yet another object of this invention is to provide a hog barn of the class described, wherein a series of pens are radially arranged in the enclosure contemplated hereby, said pens being provided for farrowing purposes, and when farrowing is accomplished, the pens can be in effect elimi-

2

nated by raising the closures constituting the same and thus providing a large area over which the pigs can roam and have access to feed and water.

Another important object of this invention is to provide manure removal means which eliminate the necessity to handle the same in the usual manual manner, by reason of the fact that a suitable floor construction is provided which will facilitate the gathering of the manure, the manure is transported to a place remote from the floor, compressed and available for fertilizing purposes thereafter.

Yet another object of this invention is to provide a novel structure, embodying elements which are easily assembled and disassembled as may be necessary, all the various factors being designed for production manufacture whereby large numbers of the barns contemplated hereby may be erected in a very quick manner and supported with a minimum amount of foundation preparation.

These and other objects will be accomplished as set forth in the specification appended hereto and disclosed in the drawings wherein:

FIGURE 1 is a vertical sectional view taken about on the line 1—1 of FIGURE 2 looking in the direction of the arrows.

FIGURE 2 is a transverse sectional view of the disclosure of FIGURE 1 illustrating the relationship of the various parts and the arrangement thereof.

FIGURE 3 is a fragmentary sectional view taken about on the line 3—3 of FIGURE 1 looking in the direction of the arrows.

FIGURE 4 is a fragmentary sectional view taken about on the line 4—4 of FIGURE 1 looking in the direction of the arrows.

FIGURE 5 is a fragmentary vertical sectional view taken about on the line 5—5 of FIGURE 2 looking in the direction of the arrows.

Referring now to FIGURES 1 and 2 particularly, the barn of this invention is shown as being of generally circular configuration and supported upon peripheral posts 1, there being four of these shown and a central post 2, suitably driven into the ground or other location and spaced about as indicated herein.

The barn itself is a circular enclosure as is suggested, including a peripheral wall 3 which is in turn supported on the upper ends of the posts 1, and in turn has engaged therewith a conically shaped roof 4 sloping upwardly toward the center and having an opening 5 at the upper end thereof for purposes which will be subsequently set forth.

Suitably arranged within the wall 3, which is shown as being of a corrugated type, are the floors designated 6 and 7 generally, the floor 6 being what may be termed a solid floor in which a suitable number of segments such as is indicated in FIGURE 2 and denoted 8 are provided, these being substantially identical and including flanged edges 9 by which adjoining panels or segments 8 may be connected together. The outer edges obviously will be supported in a suitable manner by engagement with the wall 3 and the posts 1 supporting the same and at the center engaging a sump denoted 10, the sump 10 in turn being supported at 11 on the post 2. Thus the segments 8 form a continuous circular floor which as shown in FIGURE 1 slopes toward the sump 10 for purposes which will be subsequently set forth. Preferably this floor is porcelain enamel coated and is intended to provide a means to collect manure which is dropped on the floor 7 now to be described.

The floor 7 is similarly formed to the floor 6 just previously described in that this floor 7 is formed in segments denoted 12, and including flanged edges 13 for connection to adjacent flanges of identical segments 12, but in this instance the segments 12 are formed of fo-

raminous material which is porcelain enamel coated and of sufficient strength to support hogs thereupon. The panels or segments 12 are in turn suitably supported at their outer portions by engagement with the wall 3 and at their inner portions engage a tubular member 14, which member surrounds an opening formed by the inner ends of the segments 12 and is in contact with a ring 15 to which the inner ends of the segments 12 are in turn fastened. The ring 15 is in turn connected by suitably upwardly extending brace members 16 to an upper extension 17 of the post 2.

The segments 12 are supported along their length by means of suitable trusses 18, fastened in any preferred manner at the inner ends to the ring 15 and at the outer ends to the wall 3 as will be readily understood.

With the foregoing structure generally in mind, it will be apparent that a generally cylindrical enclosure is provided having a floor of foraminous nature and on this floor are provided in turn a series of upstanding posts 20 spaced far enough from the wall 3 so as to provide a passageway thereabout of circular nature, and suitably spaced inwardly therefrom at 21 are other posts which are engaged with flanges such as 22 at their lower ends, the posts 20 being similarly engaged with similar flanges 22.

As will be observed, a number of these posts 20 and 21 are arranged around the floor 7 and extend upwardly therefrom, certain of these members, in pairs as indicated in FIGURE 2 providing a pen having the sides 23 therefor, such sides being comprised of tubular parts including an upper rail 24, a lower rail 25 and a series of vertically extending tubular rails 26 extending therebetween and fastened thereto in any suitable manner.

A further tubular part 27 extends between one of the vertical rails 26 and a further tubular member 28 which surrounds the posts 20, a tubular member 29 at the inner end of the side 23 being similarly arranged and movable on the vertical post 21. It will thus be understood that the sides 23, one of which has just been described, are susceptible of sliding upwardly and downwardly on the posts 20 and 21, there being suitable connecting members such as 30 extending transversely as indicated in FIGURE 2 between the sides 23. Thus basically the sides 23 and parts 30 will be susceptible of movement upwardly and downwardly as a unit and if desirably moved upwardly so as to provide a clear space beneath the same, in contrast to the position shown in FIGURE 1, suitable means to maintain the sides of the pen in the raised position will be provided in the form of pins which may extend through the posts 20 and 21 the pins being designated 31 and movable into openings provided in the posts 20 and 21 as will be readily understood.

A suitable gate structure at 32, specifically the outer end of the pen just heretofore described, will be provided so that it may be opened and maintained in shut position to confine a sow within the pen and yet permit the sow to lie down for nursing purposes when the small pigs are born. The farrowing pen which comprises the parts described heretofore, is in and of itself not specifically new but arranged in the radial manner, permits the proper circulation of the small pigs thereabout, and in order to confine the pigs with respect to each individual sow, suitable pen sides 33 are provided and arranged so that the same may be moved upwardly and downwardly in channels 34 and 35, the outer and inner ends respectively of such side pen parts 33. The pen sides 33 will be solid in the sense that they are sheet like members and they may be maintained in their upwardly arranged position by suitable pins such as the pins 31 and these pins in this case being designated 36. It will be understood that the channels 34 and 35 are suitably fastened to the posts 20 and 21 respectively and provide for the raising of the sides 33 when it is desired to provide a clear space therebeneath for general circulation of all of the pigs in a particular barn or enclosure as herein being

described. It is also feasible to provide closure parts 38 extending between the posts 20, these members 38 being removable as may be occasioned by the necessity to provide a clear circulating area or to have access to the small pigs therewithin.

It is to be understood that all of the various pens, of which there are 10 in number positioned around the center of the enclosure and thus arranged radially, are substantially identical although one may be completely omitted in order to provide access to the interior or feeding area which will now be described.

As will be understood from a consideration of FIGURE 1, a central area generally designated 40 is provided, this being known as the feed area and having certain feeding means therewithin specifically including a feed trough 41 of channel-like nature, extending around the area and being suitably fastened to the inner posts 21 so as to be supported at any preferred height above the floor 7.

Positioned beneath the trough and having access thereto are suitable feeders 42, being substantially identical and providing for the dropping down therewithin of feed and access thereto by raising a cover such as indicated in FIGURE 1 at 43.

This arrangement will provide means to feed the pigs either from the pen areas which have been described, or in the event the pen areas are arranged so that the pen parts are above the floor and thus afford free circulation of the pigs, the inner portions of these feeders 30 include similar doors 44 to the door 43 previously mentioned to provide access thereto.

In addition it should be noted that whereas one of these pen areas may be omitted in order to provide access to the feeding area 49, this will in turn provide access by 35 the small pigs or any pigs in fact to the feed doors 44 and thus a greater quantity of feed be made available for the hogs as they grow older.

A suitable water trough may be provided along side the member covered by the cover 43 and receive its water by reason of a ring of pipe indicated at 45 and being supported at the upper ends of the posts 21, the water supply being directed thereto in any preferred manner not specifically shown and being carried therefrom by suitable piping which will be understood by those skilled in the art.

In order to supply feed to the trough 41, a suitable feed bin 50 is shown as being of generally conical nature and supported at the top of the conical roof 4, such feed bin being connected to the roof and in turn supported from a tubular member or central support 51 by means of the braces 52 extending therefrom and connected in any preferred manner to the wall 53 of the bin 50.

The lower end of the bin 50 is open and adapted to direct feed into a distributor hopper 54 of cylindrical nature, supported on suitable bearing means 55 likewise fastened to the central support 51 in a manner to facilitate the rotation of the distributor 54. The distributor means 54 include a tubular supply member 56 extending out of the bottom thereof, the bottom being angled as indicated at 57 to cause the feed to move into the tube 56 and thence downwardly to the trough 41 previously mentioned.

Extending upwardly into the lower portion of the bin 50 is an agitator arm 58 which rotates with the distributor member 54 and breaks up the feed which might have a tendency to bridge at the lower end of the bin 50 if this was not provided.

In order to drive the distributor means 54, a suitable motor 60 is provided, suspended from a bracket 61 attached to the wall 53 of the bin 50, and by means of a suitable reduction gear 62, and chain and sprocket connection 63 which extends around the distributing means 54, effect the rotation desired. In order to control the operation of the motor 60 by reason of the condition of the feed or quantity of feed in the trough 41, a suitable

pressure switch 64 is provided mounted in the trough so that as the feed reaches a certain height it actuates the same and by means of suitable connections to the motor regulate the rotation of the means 54 and supply of feed therethrough. Suitable slip ring connection such as 65 may be advantageously supplied for this purpose.

In order to supply feed to the bin 50, a suitable cover 66 is provided and arranged so that a conveyor can direct feed through the opening 5 provided in the roof 4.

The central support 51 is a large diameter tube as previously suggested, and is carried on the upper end of the support extension 17, acting as a structural member as well as a means for ventilating the interior of the enclosure or barn here being described.

For the purposes hereof, the lower end of the tube 51 is perforated or provided with a series of holes 67 of suitable size and in sufficient quantity to enable a large volume of air to be directed therethrough, and arranged to slide upwardly and downwardly over the outside of the tube 51 is a suitable hood 68 which may effectively collect the air in the interior of the enclosure and direct it to the openings previously mentioned.

In addition a sleeve 69 may be provided so that it can be slid upwardly and downwardly and thus regulate the number of holes 67 exposed and providing for movement of air therethrough. The sleeve 69 may be frictionally engaged with the tube 51 or in any other manner suitably arranged to provide for positioning in various positions thereabout and thus the amount of air escaping through the member 51.

At the upper end the member 51 may be provided with a suitable fan 70 which will in turn exhaust the air through a hood 71.

In order to provide for a supply of air to the interior of the barn, the wall 3 or side 3 may be provided with a series of inlet pipes 72, in which dampers of any preferred form indicated at 73 may be supplied and the dampers susceptible of positioning to regulate the amount of air flowing through the tubes 72. The tubes 72 may likewise be equipped with suitable filtering means in the form of filter material 74 for various purposes. The necessity to provide air to the interior of the building will be readily understood and it will be controllable by these members 72 in conjunction with further members 75 provided below the floor 7 and of the same configuration and including the same elements as the member 72 just previously mentioned and specifically a damper 76 therein with suitable filtering material 77 likewise being provided.

With the foregoing arrangement it will be understood therefore that the varying weather conditions suitable draft may be induced through the openings provided by the members 75 and escape of the air by circulating means through the openings 67 in the tube 51 thence upwardly and outwardly through the hood 71. Conversely where it is desired to maintain the temperature within the enclosure at a somewhat higher level, the members 75 may be closed by the damper 76 therein, and the members 72 opened to provide enough air for air supply purposes and yet maintain the temperature at the lower portion of the enclosure at a suitably high enough elevation to prevent any ill effects on small pigs therewithin. This of course may be varied in accordance with the varying conditions and regulation of the flow of air effected by adjustment of the sleeve 69 over the opening 67 as well as the hood 68 in conjunction therewith.

The construction and operation of the manure removal means which involves broadly manure collecting means which are arranged beneath the floor 7, embodying as these means do, certain novel instrumentalities for eliminating a very material percentage of the manual labor usually involved in such operations.

Referring therefore to FIGURE 1 particularly, it will be seen that a screw conveyor member 80 extends radially from the center support 2, and is adapted to be revolved

therearound by suitable motor 81 which is mounted on a bracket 82, the bracket in turn being suitably supported for rotation upon collar or bearing members 83. The motor 81 drives a V-belt 84 which in turn operates a pulley arranged on the shaft 85 around which the screw flights 86 are supported. This screw is preferably a flexible or rubber screw member and by reason of rotation of the same will also be compelled to move bodily about the center support 2 as a pivot, the rotation of the screw itself being such as to cause the manure to be deposited in the sump 10 previously referred to.

As indicated in FIGURES 3 and 4, the sump 10 is arranged in such a manner that the manure will be in turn caused to move onto a further screw conveyor member

15 87 including the conduit 88 in which the conveyor member is adapted to rotate and further having a screw member 89 rotatable therewith by means of a suitable motor 90 and connected in any preferred manner to a suitable source of current supply.

20 The screw 89 will pick up the manure deposit in the sump 10 and transfer it to the left as viewed in FIGURE 1 into another manure collecting unit to be described more particularly subsequently and denoted 91. Both liquids and solids are directed to and through the screw conveyor 89 and to the collector unit 91.

As viewed in FIGURE 5 and likewise in FIGURE 1, the collector 91 includes a trough-like member 92 at the bottom of which is a collector area or section 93, with a suitable outlet 94 to permit liquids to escape therefrom and confining the solids within the compressor unit 95 to be subsequently described.

35 The unit 91 is arranged so as to collect all of the manure in an area through which all of the hogs are directed on their way into the barn, this area being designated 96 and availed of to keep records, and to provide for washing the animals preliminary to their confinement in the closure and subsequent thereto if necessary. The shed-like part 96 includes the floor 97 of foraminous nature and porcelain enamelled as is the floor 7 with an entrance being provided at 98 to provide access to this shed 96 and through the shed 96 and an opening 99 therein into the interior of the enclosure in general.

40 Adverting now to FIGURE 5, the compressor unit 95 is comprised of a conduit 100 in which is arranged a screw conveyor consisting of three sections, a section 101 of a fairly low pitch, a section 102 of steeper pitch and a section 103 of much steeper pitch with respect to the flights thereof. Therefore as the solids are moved by the flight 101, into the part 102 and thence to the part 103, because the exit end of this conduit 100 denoted at 104 is restricted gradually, the solids are compelled to be compressed therewithin and permit all of the liquid to flow downwardly and out through the opening 94 with the solids in compressed state being ejected from the nozzle end 104 at 105. Here the material now compressed may be packaged or otherwise removed for fertilizing purposes.

45 As indicated in FIGURE 1, the shed enclosure 96 is supported by connection to the wall 3 and on a post such as 106 the floor being of any preferred construction in general and obviously arranged to support people having occasion to walk thereover.

50 In view of the foregoing it will be understood that all of the various necessary functions involved in raising hogs from the time of farrowing through the period of fattening and until they are ready for market, has been provided for in the disclosure hereinbefore set forth in detail, and in such a manner that the units are small enough and yet economical enough to operate as to reduce the possibility and even likelihood of disease doing any substantial damage, by reason of the fact particularly of course that the sanitary conditions and the living conditions under which the hogs must be raised are superior in all aspects to those presently known and availed of.

I claim:

1. In a stock barn of the class described, in combination, a main enclosure, a series of radially arranged stock pens therein, said pens having a common foraminous floor therefor, central feeding means for said pens adjacent the axis about which they are located, a central axial structural support connected to said floor and feeding means, manure collecting means beneath the foraminous floor aforesaid, means to convey the manure away from the collecting means, the central feeding means comprising a feed bin supported centrally above the pens by a support extending through said bin, distributing means arranged to receive feed from said bin and operable about said support, trough means to receive feed from the distributing means, feed hoppers connected to the trough means to receive feed therefrom, means to carry feed from the distributing means to the trough means aforesaid, a central support extending through the feed bin, said support providing for exhaust of air through the same, said bin supported on said support, said distributing hopper carried by the support, and means carried by and operable on rotation of the hopper to agitate feed therein to prevent bridging thereof.

2. In a stock barn of the class described, in combination, a main enclosure, a series of radially arranged stock pens therein, said pens having a common foraminous floor therefor, central feeding means for said pens adjacent the axis about which they are located, a central axial structural support connected to said floor and feeding means, manure collecting means beneath the foraminous floor aforesaid, means to convey the manure away from the collecting means, said support providing the support for the floors aforesaid, said support likewise extending through and supporting portions of the feeding means, said support further including means to regulate ventilation of the enclosure, whereby heated air is exhausted from the enclosure.

3. The combination as claimed in claim 2, wherein a generally conical roof extends from the enclosure, the central support includes an enlarged tubular member extending upwardly centrally of the enclosure through the roof thereof connected thereto and providing structural support therefor, openings are formed in the member near the lower end thereof to provide for air flow into the member, means are provided to regulate flow through said openings, and hood means are positioned at the upper end of said member.

4. The combination as claimed in claim 3, wherein the enclosure is provided with a series of air supply openings

in the wall thereof above and below the foraminous floor and means to regulate air flow through said openings.

5. In a stock barn of the class described, in combination, a main enclosure having a substantially circular wall therefor, a series of support parts spaced beneath said wall, a central support, a solid floor carried at its periphery on said supports and at its center on said center support, a foraminous floor spaced above and coextensive with the solid floor and similarly supported, said foraminous floor in turn supporting a series of radially arranged pens thereon, central feeding means in said enclosure at the inner ends of the pens aforesaid, a conical roof engaged at its periphery with the wall and extending upwardly toward the center, means extending upwardly from the central support for supporting at least a portion of the central feeding means, said means comprising a tubular part, said part having ventilating openings within the enclosure and extending through the roof, whereby to provide for air passage, means to regulate the ventilating openings, and a hood means at the upper end of the part.

6. The combination as claimed in claim 5, wherein the central feeding means include a bin, the bin is at least partially supported on the tubular part, and feed delivery means are likewise rotatably supported on said part.
